UNITED STATES PATENT OFFICE.

NORA L. SHANKLAND, OF NEWTON, IOWA.

WINDOW STOP.

Application filed November 23, 1921. Serial No. 517,222.

To all whom it may concern:

Be it known that I, (Mrs.) NORA L. SHANKLAND, a citizen of the United States, and a resident of Newton, in the county of 5 Jasper and State of Iowa, have invented a new and useful Window Stop, of which the following is a specification.

My invention relates to window stops and its principal object resides in the provision 10 of a device of this character which will permit either sash to be raised a predetermined distance for ventilating purposes.

A further object of the invention resides 15 in the provision of a window stop embodying a pair of hinged elements, one of which being attached to one of the window sashes and the other being adapted to be swung to a position at right angles to one sash to overlie the other sash and thereby prevent 20 either sash from being opened sufficiently to permit a person to pass through the window. With the preceding and other objects and advantages in mind, the invention consists 25 in the novel combination of elements, construction and arrangement of parts and operations to be hereinafter more fully described, claimed and illustrated in the accompanying drawing, wherein:

Figure 1 is a perspective of the device attached to a window and arranged in locked position;

Figure 2 is a similar view illustrating the device in unlocked position;

Figure 3 is a side elevation of the device; 35 Figure 4 is an edge elevation of one of the elements of the invention; and

Figure 5 is an edge view of the wear plate embodied in the invention.

Referring in detail to the drawing where- 40 in similar characters of reference designate similar parts throughout the several views, the numeral 5 designates the upper sash of a window while 6 designates the lower sash.

My improved stop comprises a plate 10 45 bent intermediate its ends to afford a channel-shaped member or keeper 11. This plate 10 is secured by fastenings 12 to the inner face of one of the side rails of the upper sash 5 and as illustrated in Figure 1 the 50 plate 10 extends to the sash. A plate or abutment is designated at 13 and is hingedly connected, as at 14, to the plate 10. Carried by the plate or abutment 13 is an outstanding pin 15 disposed in horizontal alinement with the channel-shaped member or keeper 11. In order to lock the plate or abutment

13 in the position shown in Figure 1, a locking bolt 16 is provided having a longitudinal slot 17 through which the pin 15 extends. This locking bolt 16 is formed with a right 60 angularly disposed finger engaging element 18 at one end whereby to move the locking bolt longitudinally into the channel-shaped member or keeper 11, or to the position shown in Figures 2 and 3. 65

Secured to the upper face of the lower sash 6 is a wear plate 19 provided with a transverse depression 20 in which one end of the abutment is adapted to engage upon the lowering of the sash 5 and the raising of the 70 sash 6.

With the parts in the position shown in Figure 1, it will be manifest that the sashes may be moved only a slight distance with respect to each other. When the device is 75 not in use, the hinged plate or abutment 13 is swung inwardly to lie against the inner face of the side rail of the sash 5 as shown in Figure 2.

It is to be understood that the form of my 80 invention herein shown and described is to be taken as a preferred example of the same, and that various changes in the shape, size and arrangement of parts may be resorted to without departing from the spirit of the 85 invention or the scope of the subjoined claims.

Having thus described my invention, what I claim as new and desire to secure and protect by Letters Patent of the United States, is: 90

1. A window stop comprising a plate to be secured to one of the side rails of the sliding window sash, a keeper formed therein, an abutment hinged to the plate and capable of being swung outwardly to overlie the other sash and capable of being swung inwardly against the plate when not in use, and a locking bolt slidably and pivotally mounted on the abutment for engagement in the keeper to retain the abutment in operative 95 position and adapted to be swung parallel to the plate when not in use.

2. A device of the character described comprising a sheet metal plate adapted to be mounted upon one of the side rails of a sliding window sash and bent intermediate its ends to afford a channel-shaped keeper, a sheet metal abutment hinged to the plate and adapted to be arranged in a position to overlie the upper end of the other sash, an outstanding pin carried by the abutment, a bolt provided with a longitudinal slot through 100 105 110

which the pin extends, the bolt being adapted to be received in the keeper to retain the abutment in operative position and adapted to be retracted and swung to a position to extend longitudinally of the abutment when the latter is arranged in inoperative position.

3. A device of the character described including a pair of plates hingedly connected 10 and one of which being adapted to be secured to a window sash, the other being adapted to be swung to a position to overlie the other sash and thereby holding the two sashes against relative movement, one of the 15 plates being formed with a channel shaped guide and a locking element slidably carried

by the other plate to be received in the guide to hold the two plates rigid.

4. In a device of the character described, a pair of plates hingedly connected and one 20 of which being adapted to be attached to a window sash and the other being adapted to be disposed in the path of the other window sash and constituting an abutment, a keeper carried by one of the plates and a locking 25 element slidably and pivotally connected with the other plate and adapted to be received in the keeper to hold the two plates rigid and adapted to be swung to a position to extend parallel to the other plate when 30 not in use.

NORA L. SHANKLAND.
